UNITED STATES PATENT OFFICE.

JAMES C. BLAIR, OF TOLEDO, OHIO, ASSIGNOR TO THE LIBBEY-OWENS SHEET GLASS COMPANY, OF TOLEDO, OHIO, A CORPORATION OF OHIO.

METHOD AND APPARATUS FOR FORMING SHEET GLASS.

Application filed February 28, 1925. Serial No. 12,232

The present invention relates to sheet glass apparatus, and has particular reference to means for preventing the narrowing of the sheet after it has been drawn from a mass of molten glass.

An important object of the invention is to provide a sheet drawing apparatus wherein a sheet of glass is continuously drawn from a mass of molten glass, and includes 10 means for forming relatively thick edges thereon, and means arranged above the edge forming means to prevent narrowing of the sheet.

A further object of the invention is to 13 provide stationary shoe members adapted to contact with the edges of a sheet of glass, being drawn from a mass of molten glass in a manner that the edges will be held against lateral movement, thus preventing 20 narrowing of the sheet.

Still another object of the invention is to 25 provide a sheet drawing apparatus for continuously drawing a sheet from a source of molten glass, and includes means for forming beaded edges on the sheet, and adjustable preferably internally cooled metallic shoes adapted to contact with both sides of the sheet at the edges thereof to hold the sheet to width by preventing lateral movement 30 of the beaded edges.

Other objects and advantages of the invention will become apparent during the course of the following description.

In the drawings wherein like numerals 35 are employed to designate like parts throughout the same,

Fig. 1 is a vertical transverse section through a portion of the apparatus showing my improved construction in use.

40 Fig. 2 is an enlarged view showing the apparatus in use and mounting therefor.

Fig. 3 is a top plan view thereof.

Fig. 4 is a top plan view partly in section for the purpose of illustration,

45 Fig. 5 is an end view of the device.

Fig. 6 is a front elevation showing a slightly modified arrangement.

Fig. 7 is a top plan, partly in section, 50 showing the type of edge which may be formed.

Fig. 8 is a fragmentary perspective view of another form of apparatus.

Fig. 9 is a side elevation thereof, and

55 Fig. 10 is a view showing the use of plane edge forming rolls.

In the patent to Colburn, 1,248,809, granted December 4, 1917, a sheet 15 is continuously drawn from a source of molten glass 16 contained within a pot 17. The pot 17 is in open communication with one end of 60 a tank furnace by which means the source of molten glass 6 is continuously replenished. In the Colburn process, knurled rolls are placed at both ends of the sheet supplying meniscus 18 to create a drag and retard the movement of the glass being entered into the border portions of the sheet 15. These rolls are provided to prevent narrowing of the sheet. The sheet is drawn in the vertical plane for approximately two feet where it is deflected over a bending roll 19 whereby the sheet can be run in a horizontal plane over a flattening table and through an annealing leir. In actual practice the sheet when it reaches the bending roll is somewhat narrower than the sheet at its base where it leaves the knurled rolls above referred to.

It is the aim of the present invention to prevent this narrowing of the sheet after it leaves the rolls provided to form an edge thereon. It is thought that this contraction of the sheet has a tendency to introduce wave formations therein, while at the same time it reduces the size of the usable sheet produced by the machine. Although the present invention is shown as being used in connection with the Colburn process it is to be understood that the same principle can be successfully used in any type of sheet drawing apparatus wherein it is necessary to maintain the sheet to width by forming relatively thick edges thereon.

I have deemed it desirable to alter the construction of the knurled rolls used to form an edge on the sheet to the extent 65 shown in Figs. 1 and 2, wherein the knurls 20 are provided with the reduced preferably smooth portions 21 between its ends so that the sheet edge passing between a pair of rolls will have a bead 22 formed thereon similar to that shown in Fig. 7. Although this bead formation 22 is desirable it is not essential to the successful operation of my apparatus. After the sheet edges are formed by being passed between the rolls 20 they are pulled 105 through the shoe-like members 23 which are arranged to form substantially a channel. The shoe-like members 23 are adjustably mounted to permit various adjustments with respect to the sheet 15, but are held against 110

relative movement during their operation and contact with the sheet. The shoes 23 are arranged as shown in Fig. 7, and comprise the arms 24 which are preferably formed integral with the shoe-like ends 25 which contact with the edges of the sheet. The members 23 are preferably hollow forming passageways 26 through which a cooling medium may be circulated as through the conduits 27. Air or cold water may be used for this purpose. The contacting faces 27 are preferably smooth and are adapted to contact with the edge of the sheet in a manner to prevent lateral movement thereof, thus overcoming the tendency for lateral movement of the edges which permit the sheet to narrow up from the time it leaves its sheet source 18 until it reaches the bending roll 19.

As shown in Fig. 2, the arms 24 have connection with a toggle 28 carried by the shaft 29 supported in the journals 30. The shaft 29 is provided with the screw portion 31 whereby a spring 32 may be positioned between one of the journals 30 and a nut 33 carried on the screw portion 31. The journals 30 are carried by the slide 34 supported on the base 35, and adjustably associated therewith by means of the screw-threaded shaft 36 passing through the base 34 and journaled in the support 35. The device may be moved as a unit through means of the worm 41 carried by the shaft 37 and rotatable as through the operating wheel 38, the said worm 41 meshing with the gear 39 which is carried upon the shaft 40. As is clearly shown in Fig. 3, the arms 24 are pivotally connected to the yoke 28 so that the shoes 23 may be moved to and from each other to permit any size sheet to be drawn therebetween. A coil spring 42 is provided to normally urge the shoes 23 toward each other as through the stationary shaft 29 and the rigid portion 43. A set screw 44 operable through the ear 45 and abutting against the lug 46 is provided to restrict movement of the shoes toward each other, thus preventing an action too severe upon the edges of the sheet.

The shoes are mounted in a position as to contact with the edges of the sheet immediately after they have been formed, and the edges are drawn between the shoes, absorbing sufficient heat therefrom and positively holding the same in a manner that they will not be free to move toward each other, thus preventing the sheet from narrowing in. It is desirable that a beaded edge 22 be formed so that the shoes can be engaged with the edges of the sheet as is shown in Figs. 7 or 8, the bead providing a further assurance that no lateral movement will be permitted.

In Fig. 6 the shoes are shown as contacting with the edges of the sheet right down to the base of the meniscus so that the knurled rolls 20 can be dispensed with.

In Figs. 8 and 9, the knurled rolls have been replaced by preferably refractory blocks 47 which are partially submerged in the glass in a manner to create a drag for retarding the movement of the flow of glass into the border portions of the sheet, thus forming an edge similar to that edge formed by the knurled rolls except for the fact that it will be more smooth and uniform. Refractory blocks 47 may be modified to any desired shape or curvature, and are merely shown to indicate that the shoe members 23 can be adapted to work either with the knurled rolls, smooth rolls 48 shown in Fig. 10, or the refractory blocks 47 disclosed in Figs. 8 and 9. The refractory blocks will form preferably a beaded edge, after which the beaded edges are engaged by the shoes 23 to prevent narrowing of the sheet.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. In sheet glass apparatus, means for drawing a sheet from a mass of molten glass, positive means for forming edges on said sheet, and means above said edge forming means for preventing lateral movement of said edges.

2. In sheet glass apparatus, means for drawing a sheet from a mass of molten glass, means for forming thickened edges on said sheet, and means arranged above said edge forming means for preventing narrowing of the sheet.

3. In sheet glass apparatus, means for drawing a sheet from a mass of molten glass, means for forming relatively tough edge portions on the sheet, and means above said edge forming means adapted for frictional engagement with said edges to prevent narrowing of the sheet.

4. In sheet glass apparatus, means for drawing a sheet from a mass of molten glass, means for forming relatively thick edges on the sheet, and stationary members above the edge forming means and contacting with said edges to prevent narrowing of the sheet.

5. In sheet glass apparatus, means for drawing a sheet from a mass of molten glass, means for forming beaded edges on the sheet, and stationary members above the edge forming means and contacting with the beaded edges to prevent narrowing of the sheet.

6. In sheet glass apparatus, means for drawing a sheet from a mass of molten glass, means for forming relatively thick

edges on the sheet, and means arranged on both sides of each edge and above the edge forming means to prevent narrowing of the sheet.

5 7. In sheet glass apparatus, means for drawing a sheet from a mass of molten glass, means for forming relatively thick edges on the sheet, and a stationary shoe arranged on both sides of each edge and 10 above the edge forming means for preventing narrowing of the sheet.

8. In sheet glass apparatus, means for drawing a sheet from a mass of molten glass, and stationary shoes arranged along 15 the edges of the sheet until they become substantially set to prevent narrowing thereof.

9. In sheet glass apparatus, means for drawing a sheet from a mass of molten glass, and stationary adjustable shoes contacting with the edges of the sheet, said 20 shoes being long enough to contact with the sheet edges until they are stiff enough to prevent narrowing of the sheet.

10. In sheet glass apparatus, means for 25 drawing a sheet from a mass of molten glass, means for forming relatively thick edges on the sheet, stationary adjustable shoes arranged above the edge forming means and contacting with the thickened 30 edges to prevent narrowing of the sheet, and means for circulating a cooling medium through the said shoes.

11. In sheet glass apparatus, means for 35 drawing a sheet from a mass of molten glass, rotatable rolls for forming relatively thick edges on the sheet, and stationary flat members contacting with the sheet above the rolls to prevent narrowing of the sheet.

12. In sheet glass apparatus, means for

40 drawing a sheet from a mass of molten glass, rotatable grooved rolls for forming beaded edges on the sheet, and stationary shoe members contacting with the sheet above the rolls to prevent narrowing of the sheet.

45 13. In sheet glass apparatus, means for drawing a sheet from a mass of molten glass, rotatable knurled rolls having grooves therein for forming beaded edges on the sheet, substantially flat members arranged 50 above the rolls and contacting with the beaded edges for preventing narrowing of the sheet, means for adjustably mounting the said members, and means for cooling 55 the same.

14. The process of producing sheet glass, consisting in drawing a sheet from a source of molten glass, forming relatively thick edges on the sheet being drawn, and then 60 passing the edges between stationary means to prevent narrowing of the sheet.

15. The process of producing sheet glass, consisting in drawing a sheet from a source of molten glass, forming beaded edges on 65 the sheet, and then passing the beaded edges between stationary means to prevent narrowing of the sheet.

16. The process of producing sheet glass, consisting in drawing a sheet from a source of molten glass, forming beaded edges on 70 the sheet, and then passing the beaded edges between heat-absorbing and frictional contacting means to prevent narrowing of the sheet.

Signed at Toledo, in the county of Lucas, 75 and State of Ohio, this 26th day of February, 1925.

JAMES C. BLAIR.
